UNITED STATES PATENT OFFICE.

REINHOLD BOEKLEN, OF NEW YORK, N. Y.

IMPROVEMENT IN MACHINES FOR SWAGING SCREW-THREADS ON BOLT AND SCREW BLANKS.

Specification forming part of Letters Patent No. **139,861**, dated June 17, 1873; application filed October 2, 1872.

To all whom it may concern:

Be it known that I, REINHOLD BOEKLEN, of New York, in the county of New York and State of New York, have invented certain new and useful Improvements in Machines for Rolling Screw-Threads on Metal; and I do hereby declare that the following is a full, clear, and exact description thereof that will enable others skilled in the art to which it appertains to make and use the same, reference being had to the accompanying drawings and to the letters of reference marked thereon, which form a part of this specification.

This invention relates to an improvement in machines for rolling screw-threads on metal rods where required; and consists in combining, with a vibrating and one or two stationary dies, a crank movement, and in connecting with the vibrating die one or more annular flanges and connecting mechanism, as herein-after more fully described and pointed out by the claim.

Figure 1 represents a side elevation of a machine embodying my invention. Fig. 2 is a partial transverse vertical section. Fig. 3 is a longitudinal section through center of die D; and Fig. 4 is a longitudinal section of a modification.

A represents the bed piece which supports the frame or stand B, which may be of any suitable or desired construction. C C represent the stationary dies which are secured to the stand or frame B, which may be arranged to be adjusted by set-screws in the ordinary manner. D represents the vibrating die, which is supported upon the shaft E, and has screw-threaded surfaces corresponding to those upon the face of the stationary dies for cutting threads. E represents the shaft upon which the vibrating die is mounted. Said shaft has a bearing in the frame or stand A, with another suitable bearing, as shown in dotted lines, Fig. 4. F represents a crank, by which motion is imparted to the vibrating die through the shaft E. G represents a connecting-rod or pitman, connected with the crank F. H represents the hopper through which the blanks are fed and regulated in proper position by the arms I. J represents two springs coiled around shaft E in opposite directions, one end of each of these springs

being attached to the stud K, secured upon the inside of the guide L; the object of the springs being to throw the vibrating die D to its normal position and allow the guide to yield to the motions of the blank between the dies. The outer surface of the guide L is provided with annular flanges c c, which may be adjustable to correspond to the head of the bolt or screw, and receive the same, as shown in Fig. 2.

The blanks are fed from the hopper H, one by one, into one of the pockets a. The die D is then vibrated, the blank passing between the said die and one of the dies C, and the thread is by this means formed upon the blank, and the same is discharged at the point b. When the die D is in position to discharge a screw from one of its pockets, the other pocket is brought directly under the hopper H and receives a blank which is to be threaded by the opposite die as the die D is brought back to its first position; thus a blank is threaded by every alternate motion of the vibrating die D. The distance between the pockets a a is equal, or nearly equal, to the length of the face of one of the dies C.

The advantages gained by using crank movements for this class of machines are, that by this means the power can be used direct from a cylinder of an engine or main shaft without interposing cogs or belts, which are objectionable in machines doing heavy work; and by having the crank at or passing its dead-center when one of the pockets a is beneath the hopper H, as shown in Fig. 1, the crank F and die D remain sufficiently still for an instant for the pocket to receive the blank from the hopper, then at the beginning of the return stroke of the piston-rod the motion of crank F and die D is at first slow and then gradually increases, thus bringing the blanks between the dies slowly, and by a gradually-increasing speed. This prevents the machinery from being broken, as heretofore, where cogs or belts were used and the blank brought suddenly between the dies, and especially in the use of cogs where the slack or space between the cogs causes a jerking motion of the moving die as the blank is brought between the dies.

The modification shown in Fig. 4 embodies

the same principle as that above described, and is operated by the same means. The modification consists simply in setting the dies C' C' beneath the die D, with their lower ends nearly meeting below, leaving a discharge-opening, a' directly under the die D. By doing this it will necessitate the use of two hoppers, H' H', one being placed at the top of each of the stationary dies C' C'. With these exceptions the operation and construction is the same as the machine above described.

There may be another guide, L, placed upon the opposite side of the vibrating die, and the dies made sufficiently wide to cut two bolts at the same time, but this I consider simply a duplication of what is shown and described.

Having thus fully described my invention, what I claim, and desire to secure by Letters Patent, is—

1. The stationary die or dies C C, and vibrating die D, provided with the guide L, the die D being operated by a crank movement directly from the rod G, substantially as and for the purpose herein specified.

2. The guide L and annular flanges c c, in combination with the springs J, hopper H, and dies D C C, substantially as and for the purpose set forth.

3. The annular guide L, with pockets a, in combination with the hopper H, when constructed as described and for the purpose specified.

R. BOEKLEN.
